UNITED STATES PATENT OFFICE.

EDWARD B. GRUNENDIKE, OF SPRINGFIELD, ILLINOIS, ASSIGNOR TO B. F. BOOTH, OF SPRINGFIELD, ILLINOIS.

AUTOMATIC VALVE FOR STOCK-FOUNTAINS.

1,127,359.

Specification of Letters Patent.

Patented Feb. 2, 1915.

Application filed February 6, 1914. Serial No. 817,085.

To all whom it may concern:

Be it known that I, EDWARD B. GRUNENDIKE, a citizen of the United States, residing at Springfield, in the county of Sangamon and State of Illinois, have invented new and useful Improvements in Automatic Valves for Stock-Fountains, of which the following is a specification.

My invention relates to improvements in stock-watering fountains and refers more particularly to automatic control valves therefor.

The object of my invention is to provide for devices of the above character an improved inlet valve which will be susceptible to direct action thereon by a float, without the use of a complexity of reciprocating parts therebetween, and which will automatically maintain the water at any predetermined level in the drinking fountain.

With the above and other objects in view, my invention consists of the details of construction, combination of elements, and arrangements of parts hereinafter described, illustrated in the annexed drawings, and pointed out specifically in the appended claims.

In the drawings, to which reference will be had, like reference characters refer to like or corresponding parts throughout the several views.

Figure 1 is a front elevation of the valve seat casting. Fig. 2 is a vertical sectional view through the valve-seat casting, taken on line 2—2 of Fig. 1, the float, valve spring and valve being shown in elevation, the dotted lines indicating the open position of the valve and float. Fig. 3 is a perspective view of the float. Fig. 4 is a longitudinal section view through the supply tank and water-fountain provided with the valve of my invention. Fig. 5 is a perspective view of the valve and stem.

Referring now to the drawings, I provide a water source 12 connected by a pipe line 20 to a stock-watering fountain 18. On the wall of the fountain 18 I provide an inlet valve casting 1 adapted to be secured over the inlet opening from the pipe line 20 by means of bolts, or other suitable means, through slots 21. On the rear side of casting 1, a cylindrical valve chamber 2 is provided, communicating with the inlet opening to the fountain, a recess 3 being formed in the inner wall of chamber 2, which recess

is adapted to receive a valve seat ring 4, preferably formed of rubber, or a like material.

Numeral 5 designates the inlet passage through the valve seat casting.

In chamber 2, I provide a cone-shaped valve 6 adapted to normally seat against the valve-seat ring 4, the apex of the cone extending toward the interior of the fountain, a valve stem 7, preferably comprising two spring metal strips, projecting therefrom through passage 5.

In order to provide means for the normal seating of valve 6 against seat 4, I employ a spring loop 11, having its end portions 8 coiled about pin 9 carried between lugs 10 on the rear face of casting 1, the central loop extending upward and about valve stem 7, while the ends of the spring are seated against the inner face of casting 1. 75 A washer 14, preferably bent on the lower edge to allow freedom of movement of the valve stem in the open position, is fitted about valve stem 7 over spring 11, and a cotter 13 passed through the valve stem 80 to secure the same in place.

I prefer to maintain a constant water level in the watering fountain at a height slightly above the inlet opening from the pipe line. I therefore provide a float 15 which is formed of wood, or suitable buoyant material, and which is hinged to casting 1, and adapted to normally occupy an approximately horizontal position on the surface of the water in fountain 18. Float 15 is hinged to casting 1 by means of two L-shaped threaded rods 16 screwed into the end of the float, slots 17 being formed in casting 1 for the reception of these rods. It will be seen that the right-angle extensions 95 on rods 16 may be readily entered into slots 17 by turning the extensions to an upright position in the float, and then elevating the float to a vertical position. After the float is in place, the angle-extensions may be 100 turned in a horizontal position, thus anchoring the float to the casting 1. A metal strip 19 is fixed on the end of the float and extended down below the lower surface thereof a sufficient distance to just engage the 105 projecting end of valve stem 7, when the float is in its normal horizontal position.

By reference to the dotted line position of float 15 in Fig. 2, it will be seen that when the drinking fountain is empty the metal 110

strip 19 will contact with the end of valve stem 7 and force valve 6 away from seat 4, against the opposite pressure of spring 11. The bent washer 14 will allow the pressure of float 15 to force the end of valve stem 7 slightly downward during this operation, and the valve will be directed outward and upward from its seat. This position of the valve will allow the water to flow from source 12 into fountain 18, the valve being raised to allow the free passage of the water. When the water level in fountain 18 has risen to the position in which float 15 is substantially horizontal, the pressure against the end of valve stem 7 will be relieved and spring 11 will draw valve 6 against seat 4, shutting off the supply of water. As the water is used from the fountain and the water level therein lowered, metal strip 19 will again directly actuate the valve open and water will be admitted.

From the foregoing it will be readily seen that my invention provides an improved inlet valve which is susceptible to direct action thereon by a float, and which will automatically maintain a predetermined water level in a stock-watering fountain.

While I have herein described and illustrated the preferred embodiment of my invention, I do not wish to be limited strictly to the construction shown, except for such limitations as the claims may import, as it is obvious that the details of construction and arrangement of the several elements may be varied in many ways.

Having thus described my invention, what I claim is:—

1. In an automatic control valve for stock-fountains, the combination of means for normally seating a valve against its seat comprising a spring having coils on its end portions and a central loop extending upward and engaging the valve stem to yield-

ingly hold the valve stem inwardly of the fountain, said coils surrounding a pin anchored between parallel lugs on the interior wall of the stock-fountain, and the ends of the spring being extended upward rearwardly of the central loop and engaged against the wall of the fountain, substantially as described.

2. In a water inlet control device for stock-fountains, the combination of a valve seat casting fixed to the wall of the stock fountain, a valve chamber communicating with the water inlet passage to the fountain, a valve seat ring in the inner wall of the valve chamber, a water inlet passage in said valve seat casting leading from the valve chamber to the interior of the stock-fountain, a cone-shaped valve positioned in the valve chamber with the apex of the valve cone extending inward into the water inlet passage, a valve stem comprising two spring members fixed to the valve and extending through the water inlet passage into the interior of the fountain, a spring mounted to the valve seat casting within said trough and engaging the valve stem to normally seat the valve against the valve seat, a bent washer and cotter carried by the valve stem over the spring, a float hinged to the valve seat casting and adapted to normally lie upon the surface of the water in the fountain in a substantially horizontal position, and a valve opening projection on the end of said float positioned to engage the end of the valve stem and to actuate the valve outward and upward out of its seated relation with the valve seat upon the lowering of the water level in the fountain, substantially as described.

EDW. B. GRUNENDIKE.
